MEANS FOR CONTROLLING HOISTS AND WINCHES

John C. Slonninger, Dallas, Tex., assignor to The Continental Supply Company, Dallas, Tex., a corporation of Delaware

Application April 1, 1950, Serial No. 153,319

23 Claims. (Cl. 254—173)

1

This invention relates to new and useful improvements in means for controlling hoists and winches.

The invention is particularly concerned with apparatus for controlling the rotation of the cable reels of well drilling rigs, and in provision for maintaining a constant rate of feed and a constant drilling load upon the drilling bit of such a rig.

One object of the invention is to provide a device of the character described including a small motor which may be driven at various ascertainable speeds and which will regulate the paying-out of cable from a reel in accordance with such speed.

Yet another object of the invention is to provide a device of the character described which may be set to maintain a given drilling load upon a drill bit, and will maintain such load by regulating the paying-out from the cable drum of a drilling rig the cable which supports the drill bit and drill stem assembly.

A particular object of the invention is to provide an improved device of the character described having a novel anchor for the dead end of the supporting cable, in which compensation may be made for the size or diameter of the cable, and which aids in the accuracy of control effected by the entire apparatus.

A further object of the invention is to provide an improved device of the character described which is light and inexpensive in structure, but which adequately controls the heavy loads involved.

A still further object of the invention is to provide an improved device of the character described which properly controls a hoist or winch, but which allows manual or other types of control to be taken over immediately.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a side elevational view showing schematically a drilling rig assembly having incorporated therein a control apparatus constructed in accordance with this invention.

Fig. 2 is an enlarged view of the cable reel controlling portion of the apparatus.

Fig. 3 is a schematic view of the assembly for controlling the flow of driving fluid to the control motor,

Fig. 4 is a view of a modified form of the brake lever coupling arrangement.

Fig. 5 is an enlarged view in elevation of a modified form of the driving fluid control mechanism.

Fig. 6 is a view of a modified form of the dead-line anchor.

Fig. 7 is a view, partly in elevation and partly in section, of a modified form of the control motor driving connection.

Fig. 8 is a vertical, sectional view of a further modification of the driving arrangement shown in Fig. 7 and illustrating the clutch operating mechanism.

Fig. 9 is an enlarged sectional view of the hydraulic cylinder and piston coupling the control mechanism to the cable drum brake.

Fig. 10 is a vertical, sectional view taken upon the line 10—10 of Fig. 6.

Fig. 11 is a vertical, sectional view taken upon the line 11—11 of Fig. 6.

Fig. 12 is a plan view, partly broken away, of the dead line anchor, and

Fig. 13 is an enlarged, fragmentary, plan view of the driving arrangement shown in Fig. 8, illustrating the clutch actuating mechanism.

In the drawings, the numeral 10 designates in general a drilling rig of the type generally employed for the drilling of wells, such as oil wells. The rig is shown in a very simplified and schematic manner for the purposes of illustration and for explanation of the mode of application of this invention.

The rig includes the usual upright derrick 11 having a crown block 12 at the upper end thereof, and a travelling block 13 suspended from the crown block by a plurality of strands of cable 14, in the usual manner. One end of the cable 14 is secured to an anchor 15, and the other end of the cable is reeled upon a drum 16. As the drum 16 is revolved forwardly or backwardly, the cable 14 is reeled in or payed out and the travelling block 13 is caused to rise or fall within the derrick 11. Of course, the drill pipe (not shown) is supported from the travelling block 13 in the usual manner and carries a drilling bit upon its lower end.

In drilling operations, the cable drum 16 is revolved by a suitable engine or motor (not shown) to reel in the cable 14, raising the travelling block 13, and the drill pipe consequently being raised within the well bore. The cable is payed out from the drum 16 simply through the action of the weight of the drill stem which pulls the travelling block 13 downwardly and draws the cable 14 from the drum. A suitable band

brake 17 is provided upon one flange of the drum 16 for controlling its movement, and the rate and degree of paying-out of the cable therefrom. This invention, in part, controls the operation of the brake 17, thereby stopping the paying-out of the cable 14 from the drum, or permitting unreeling of the cable at a rate which may be selected at will.

As shown in Fig. 2, a motive means such as an air motor 18, or any other suitable type of motor or engine adapted to be driven by fluid under pressure or other readily-controllable source of power, is provided adjacent the drum 16 and drives an operating shaft 19 through a suitable selective speed changer 20. The speed changer 20 may be any suitable or desirable type of device capable of varying the ratio between the speeds of rotation of the motor 18 and shaft 19, and may be operated by a suitable gear shift or speed changer lever 21 for selecting various ratios of speeds. A telescoping splined coupling 22 is connected to the shaft 19 and couples a second operating shaft 23 to said shaft 19. This arrangement prevents rotation between the two shafts, but permits longitudinal movement of the shaft 23 with respect to the shaft 19.

A worm gear 24 or other rotatable element is mounted upon the shaft 23 and meshes with a worm wheel 25 coupled to a suitable pulley 26. In turn, the pulley 26 is connected by a driving belt 27 to a pulley 28 mounted upon and rotating with the cable drum or reel 16. The worm wheel 25 is connected to the pulley 26 through a suitable ratchet mechanism 28', whereby rotation of the pulley 26 in a clockwise direction, as viewed in Fig. 2, is transmitted to the worm wheel 25, but rotation of the pulley in the opposite or counter-clockwise direction is unimpeded. Other rotatable elements and connections may be employed in this portion of the apparatus for accomplishing the same function. The described coupling has been found most desirable.

The shaft 23 is extended beyond the worm gear 24, being supported in a suitable bearing 29 and having its outer end 30 terminating adjacent an arm 31 or other actuating means secured to the brake-operating handle 32. With this arrangement, longitudinal movement of the shaft 23 to the left, as viewed in Fig. 2, causes the arm 31 to swing counter-clockwise and tighten the brake band 17 upon the periphery of the cable reel 16. Such tightening of the brake band slows or stops the revolution of the cable reel according to the degree of force applied to the lever 31 by said shaft 23.

In the operation of this portion of the invention, assuming that it is desired to take up or reel in cable onto the drum 16, the ordinary driving machinery is employed for this purpose to revolve the drum in a counter-clockwise direction, as viewed in Fig. 2. When this occurs, the pulleys 28 and 26 are also driven in a counter-clockwise direction, but the ratchet mechanism 28' permits the worm wheel 25 to remain at rest or to revolve slowly. When it is desired to pay out or unreel cable from the drum, however, the latter is revolved in a clockwise direction, revolving the pulleys 28 and 26 in a clockwise direction and resulting in clockwise revolution of the worm wheel 25. Such revolution of the worm wheel causes the worm gear 24 to move to the left, forcing the end 30 of the shaft 23 against the lever or arm 31, tightening the brake 17 and slowing or stopping the reel 16. In this condition of the apparatus, the motor 18 may be em-

ployed to regulate the speed of revolution of the drum 16, in that the motor may be driven at a desired speed, and by means of the speed changer 20, the shafts 19 and 23 will also be driven at a selected or desired speed. This speed of revolution of the shaft 23 creates a selected speed of revolution of the worm wheel 25, and provides for a certain speed of revolution of the pulleys 26 and 28 along with the drum 16. If the drum tends to revolve too slowly, the worm gear 24 will be revolved too rapidly by the motor 18 in relation to the speed of revolution of the worm wheel 25, and will tend to move to the right, as viewed in Fig. 2. Such movement shifts the shaft 23 to the right and releases the brake 17, thereby allowing the drum 16 to increase its speed of revolution. Should the drum tend to overspeed and unreel cable too rapidly, the worm wheel 25 will be driven too rapidly in the relationship to the speed of revolution of the worm gear 24, and the worm gear along with the shaft 23 will be shifted to the left, tightening the brake band 17 and slowing down the cable reel 16. It is to be noted that the motor 18 does not drive or revolve the drum 16, but merely serves as a means for revolving the shaft 23 and the worm gear 24, at a selected speed. The drum 16 is revolved by suitable engines or motors, or by the weight of the drill stem carried by the cable 14, and in turn, drives the pulleys 28 and 26 and the worm wheel 25. According to whether the worm wheel 25 is being revolved too rapidly or too slowly, the worm 24 and shaft 23 will be shifted to the left or to the right to increase or decrease the tension upon the brake band 17 and bring the speed of revolution of the cable drum to the proper value. Of course, the longitudinal shifting of the shaft 23 is made possible by the splined coupling 22 without requiring corresponding shifting of the shaft 19, and at the same time, the coupling effectively transmits rotative motion between the two shafts.

It is obvious that the relative pitches of the worm 24 and the worm wheel 25 may be of any selected value, and, with proper design, will eliminate any possibility of the worm being driven by the worm wheel. Thus, no matter how great the load upon the cable 14 may be, the worm 24 may be driven with a small source of power and will control the feeding out of cable from the drum without being susceptible to driving by the drum. The maximum load placed upon the driving motor 18 does not exceed that necessary to overcome the friction of the system and to permit a braking force to be applied to the brake band 17. The actual braking is done by rotation of the cable drum, and the need for heavy or cumbersome equipment is therefore eliminated. This point is emphasized by the fact that rotation of the cable drum will apply the brake even when no energy is being supplied to the driving motor. Actually, the brake is applied by the cable drum and merely released by the motor.

It is not always possible or preferable to arrange the elements precisely as shown in Fig. 2, and it is sometimes not desirable to place the worm and worm wheel mechanism upon the same side of the cable drum as the brake band 17. A modification is shown in Fig. 4, in which the shaft 23 carries at its outer end a hydraulic piston 33 enclosed within a hydraulic cylinder 34. A similar hydraulic piston 35, enclosed in a hydraulic cylinder 36, is adapted to have its piston rod 37 engage the arm 31 of the cable reel brake

band handle 32. A suitable hydraulic fluid conductor 38 extends between the cylinders 34 and 36 so that longitudinal movement of the shaft 23 and piston 33 is reflected in similar longitudinal movement of the piston 35 and the piston rod 37. The utilization of the hydraulic fluid conductor 38 permits the location of the two cylinders at remote points, whereby the operating shaft 23 need not be aligned with the brake handle arm 31, as shown in Fig. 2.

As hereinbefore stated, any suitable source of motive fluid under pressure or other power supply may be employed for driving the motor 18, and any suitable means may be employed for regulating the supply of power to the motor so as to control the speed of operation thereof. A preferred embodiment of the invention, however, includes a source of compressed air 39, as shown in Fig. 3, connected through a valve 40 to a header or manifold 41. A second header or manifold 42 is connected to the manifold 41 through a plurality of short conductors 43, each conductor having therein an orifice valve 44. The apertures of the valves 44 are of differing values, and by opening different ones of said valves or different groups of said valves, fluid under pressure may be supplied at various rates to the header 42 from the header 41. In this manner, an initial control of the volume of motive fluid is provided.

A first conductor 45 is connected into the manifold 42 and extends through a shut-off valve 46 to a supply pipe 47 leading to the motor 18. By opening the valve 46, driving fluid is supplied directly to the motor 18 through the valve 44, and the speed of revolution of the motor 18 will be controlled and regulated in accordance with the opening of one or more of the orifice valves 44. For automatic control of the motor 18, a second conductor 48 leads from the manifold 42 to a hydraulically operated valve 49. The valve includes a housing 50 having therein a sliding valve 51 of the piston type, and having a hydraulic piston 52 operatively connected to said valve. The conductor 48 is connected into one side wall of the housing 50, and a similar conductor 53 extends from the opposite wall of the housing to the pipe 47. Longitudinal shifting of the valve 51 within the housing shuts off, restricts, or regulates the flow of fluid from the conductor 48 to the conductor 53 in the manner customary in this type of valve. An adjustable spring 54 is provided within the housing for applying a load to the valve structure in opposition to the force exerted upon the piston 52 by the hydraulic fluid.

For applying pressure to the piston 52, the load upon the dead end of the cable 14 is employed. As illustrated in Fig. 1, the dead end of the cable carries a clevis 55 which is pivotally connected to the intermediate portion of an arm 56 anchored to the derrick structure and adapted to swing in a vertical arc thereabove. The outer end of the arm 56 bears upon the lower end of the piston rod 57 of a piston 58 confined within a hydraulic cylinder 59. A suitable conductor 60 extends between the cylinder 59 and the housing 50, and a body of hydraulic fluid or liquid 61 transmits force from the piston 58 to the piston 52.

With this arrangement, and when the valve 46 is closed, the operation of the motor 18 may be regulated in accordance with the load exerted upon the dead end portion of the cable 14, and it is possible to maintain a constant drilling load

upon a drill bit suspended from the travelling block 13 by means of the drill stem. It is customary to support part of the weight of the drill stem from the travelling block, and to allow part of said weight to bear against the drill bit to urge the same into the formation being drilled. Obviously, as the drill is rotated and feeds downwardly into the formation, cable must be payed out from the drum 16 to maintain the load upon the bit at a constant value. The present invention accomplishes this function by regulating the speed of rotation of the motor 18 in accordance with the load exerted upon the dead end of the cable 14.

In the event the drum 16 is paying out cable too rapidly so as to apply an excessive portion of the weight of the drill stem as a load upon the drill bit, the load upon the dead end of the cable 14 will be decreased, and the spring 54 will tend to move the valve 51 to the right, as viewed in Fig. 3, shifting the piston 52 to the right and moving the piston 58 downwardly. As this occurs, the valve moves from the wide open position, shown in Fig. 3, to a partially closed position wherein the outlet from the conductor 48 is restricted, and the flow of motive or driving fluid to the motor through the conductors 53 and 47 is diminished. The motor is thus caused to revolve at a slower speed, and the overspeeding of the drum 16 shifts the worm 24 and the operating rod 23 to the left against the brake arm 31 so that the brake band 17 is tightened and the drum 16 is slowed down. Similarly, if the drum 16 is rotating too slowly, the drill bit will dig faster than cable is payed out whereby the drilling load upon the bit will be reduced and the load upon the dead end of the cable 14 will be increased. This increasing of the load upon the cable swings the arm 56 upwardly, forcing the piston 58 upwardly and the piston 52 toward the left and reduces the restriction of the conductor 48 by the valve 51. The flow of motive fluid to the motor 18 is therefore increased as the regulating valve 49 opens, whereby the motor will be speeded up, resulting in releasing of the brake band 17 to a point at which the drum 16 revolves at the proper speed and pays out the cable 14 at the proper rate.

It is obvious that the force exerted by the spring 54 may be adjusted by means of the screw-threaded follower 62 to compensate for the varying weight of the drill stem as sections of pipe are added thereto or removed therefrom, and that a substantially constant drilling load upon the drill bit may be obtained in the manner described. At any time, the valve 46 may be opened and the valves 44 regulated to provide any desired speed of revolution of the drum 16. Similarly, the revolution of the drum 16 may be reversed at any time so as to reel in cable or to assume the weight of any sudden load placed upon the travelling block 13.

A more detailed and specific embodiment of the invention is shown in Figs. 5 through 10 of the drawings. In Fig. 5, is illustrated the preferred form of control mechanism for regulating the flow of motive fluid to the speed regulating motor. This control apparatus includes a rectangular housing 63 adapted to be mounted upon a suitable support or standard 64 and positioned at a convenient operating height adjacent the floor of the derrick or drilling rig structure. The housing includes a longitudinal horizontal partition 65 carrying a pair of posts 66 upon which a weight or scale beam 67 is mounted by means

of a suitable knife edge 68. The usual large and small weights 69 and 70, respectively, are longitudinally slideable upon individual arms 71 and 72, respectively, of the scale beam 67, and indicating scales 73 are provided for designating the weight or load being exerted by the scale beam. An indicating finger or tang 74 projects from the end of the scale beam and is confined between a pin 75 carried upon upright supports 76, and a moveable keeper 77 pivoted upon the supports 76. At the opposite end of the scale beam, the customary counterbalance weight 78 is provided, along with an adjustable balancing or zeroing weight 79.

A second pair of posts 80 project downwardly from the partition 65 adjacent its central portion, and an elongate weight lever 81 has its fulcrum or knife edge 82 bearing upwardly against the posts 80. The long arm of the weight lever 81 is operatively connected to the scale beam 67 by an adjustable link 83, and the short arm of the weight lever 81 is provided with knife edges 84 bearing against the upper end of a yoke 85 connected to the upper end of a piston rod 86. The rod 86 extends into a diaphragm housing 87 and is connected therein to a suitable flexible dia-

phragm 88. The weight and beam structure which has been described takes the place of the adjustable spring 54, previously described, and provides a means for placing a selected and exact load acting downwardly upon the diaphragm 88. For opposing this load, a suitable hydraulic fluid conductor 89 is connected into the lower portion of the housing 87 and places the housing into communication with a source of hydraulic fluid to be described hereinafter, and which exists under a pressure proportional to the load upon the dead end of the cable 14. With this arrangement, as the pressure exerted by the hydraulic fluid upon the under side of the diaphragm 88 is less than or is greater than the load exerted by means of the piston rod 86, the weight lever 81 will be caused to swing clockwise and counter-clockwise, and may be employed for controlling the rate of flow of fluid to the previously-described fluid motor.

A control valve 90, is mounted in one end of the housing 63 beneath the partition 65, substantially in vertical alinement with the adjustable link 83. The valve includes a cylindrical housing 91 having therein a cylindrical liner 92 provided with valve ports 93 and 94. A piston type valve core 95 has a sliding fit within the liner 92, and has its upper end secured to a flanged cap 96 which fits loosely over the open upper end of the housing 91. A substantially L-shaped arm 97 is pivoted to the long arm of the weight lever 81, and is constantly urged toward said lever by a suitable spring 98. A set or stop screw 99 limits the swinging of the arm 97 and provides for radial adjustment of the spring. The arm is connected to the valve core 95 by means of a flexible wire 100 of sufficient strength as not to stretch when a tension is applied thereto, but which is sufficiently flexible as to bend under compression when the arm 97 is swung downwardly. Since the outer end of the lever 81 swings in an arc rather than in a straight line, and since the valve 95 must move rectilinearly, the flexible wire 100 is employed to eliminate the need for guides and pivoted joints in the connection between the weight lever and the valve core.

Motive fluid under pressure is supplied to the device through a pipe 101 connected through a plug valve 102 to a pipe T 103. One branch of

the T 103 is connected into the valve port 93, and a suitable conductor 104 leads from the other valve port 94 to a pipe T 105. A bypass pipe 106 is provided with a shut-off valve 107 and extends between the T's 103 and 105 for bypassing the valve 90, when such is desired. A header 108, equivalent to the header 41, is connected into the T 105, and is provided with a plurality of branch conductors 109 carrying drilled orifices 110 and shut-off valves 111. The lower ends of the conductors 109 are connected into a header 112, equivalent to the header 42, and a conductor 113 leads from the latter header or manifold to the fluid motor 18.

As stated hereinbefore, the pressure exerted upon the under side of the diaphragm 88 will vary from time to time whereby the weight arm 81 will be allowed to swing clockwise or counter-clockwise. When the pressure exerted on the underside of the diaphragm is low, as occurs when too much weight is being applied to the drilling bit, the lever 81 swings clockwise which raises the valves core 95, shutting off or restricting the port 94. When this occurs, the flow of fluid through the valve to the headers and the supply pipe 113 is restricted or reduced, with the result that the revolution of the cable drum 16 is slowed down, and a portion of the weight or load is removed from the drilling bit. Conversely, if the bit is underloaded and the pressure upon the diaphragm 88 is high, the lever 81 swings counter-clockwise, exposing the port 94 an additional amount and permitting a greater flow of fluid and faster revolution of the cable drum. For convenience in operation, the valves 107 and 111 are provided with suitable operating handles or levers 114, and a pressure gauge 115 is connected into the conductor 89 for indicating the pressure being exerted therein. In accordance with the previous description of the invention, the orifice plates 110 are of various and different sizes, and opening of one or more of the valves 111 results in varying rates of flow of the motive fluid to the motor 18. When desired, the valve 107 may be opened to bypass the control valve 90 and permit the revolving of the cable drum 16 at any desired or selected speed.

A preferred embodiment of the cable anchor is shown in Figs. 6, 10, 11 and 12. The anchor includes a base plate or support 116, adapted to be anchored suitably adjacent the derrick floor or the ground surface, and having a pair of up-standing side plates 117. The plates 117 are generally triangular in shape and having extensions 118 of reduced cross-section extending outwardly of the base plate 116. A plate 119 is connected between the extensions 118 and joins the two together. A pair of cheek plates 120 are pivoted adjacent one vertical edge of the plates 117 upon a transverse shaft 119' and have their free ends projecting beneath the extensions 118. Between the plates 120, a relatively narrow flanged reel 121 is rotatably mounted and receives a number of turns of the dead end portion of the cable 14. A clamp 122 secures the projecting portion of the cable to the cheek plates, and provides an anchor for said cable.

In order to permit rotation of the reel 121 when such is desired, but to hold the reel immovable with respect to the cheek plates at other times, the reel carries a plurality of transverse openings 123 adapted to be alined with openings 124 in the cheek plates and to receive a cotter or locking pin 125 passed through the openings 124. Enlarged openings 126 in the side plates 117 fa-

cilitate insertion and removal of the pin. When the pin 125 is in place, the reel and cheek plates move together as a unit, but because of their small amplitude of movement, there is no engagement between the pin and the walls of the openings 126.

A hydraulic cylinder 128 is disposed vertically between the extensions 118 adjacent the plate 119 and is adjustably secured thereto by bolts 129 engaging in slotted openings 130 formed in lateral ribs 131 projecting from said extensions. A hydraulic piston 132 is carried within the cylinder 128 and has a piston rod 132' projecting downwardly into engagement with a plate 120' carried upon the upper edges of the cheek plates 120.

In use, the dead end of the cable 14 is received tangentially by the reel 121 and is passed there-around several times, the projecting end of the cable being secured in the clamp 122. Any upward stress or load upon the cable 14 thus tends to swing the reel and the cheek plates upwardly, as viewed in Fig. 6, and to swing the plate 120' upwardly, forcing the piston 132 upwardly within the cylinder 128. In this manner, the load placed upon the cable is reflected as the pressure exerted by the piston 132 upon the hydraulic fluid within the cylinder 128, this pressure being communicated through the conductor 89, which is connected into the upper end of the cylinder, to the underside of the diaphragm 88 in the weight control structure shown in Fig. 5.

It is to be noted that the distance between the shaft 119', which is the center about which the cheek plates 120 are pivoted upon the side plates 117, and the center of the cable 14 is much less than the distance between the shaft and the point of engagement on the piston rod 132'. With this arrangement, a considerable mechanical advantage is had, and both the dimensions of the cylinder 128 and the pressures within the cylinder are kept within reasonable limits. At the same time, the cylinder may be adjusted toward or away from the shaft 119' by means of the bolts 129 and slotted openings 130, and compensation made for the use of cables of various diameters. Since the effective lever arm between the shaft 119' and the cable 14 is viewed as extending from the center of the shaft to the axial center of said cable, provision is desirably made for adjusting the anchor mechanism in accordance with the diameter of cable in use. With this structure described, as cables of various sizes are employed, the cylinder 128 may be shifted toward or away from the shaft 119' to make proper compensation for the difference in cable diameter.

A preferred embodiment of the worm wheel and worm gear structure is shown in Fig. 7, including a speed changing device 133, having a drive shaft 134 to which is connected the fluid motor 18 (not shown in this figure). A splined operating shaft 135 extends from the speed changer 133 into a gear housing 136 within which the worm wheel 137 and the worm gear 138 are mounted. The worm gear 138 is secured upon the splined shaft 135, which is movable longitudinally with respect to the speed changer. The gear, therefore, may not revolve on the shaft, but the entire gear and shaft structure may shift longitudinally. A toothed ratchet wheel 139 is disposed centrally of the worm wheel 137, and is provided with ratchets 140 having leaf or drag springs 141 thereon. An operating shaft 142 projects from the worm gear 138 and extends into

a lateral housing 143 projecting from the housing 136. A hydraulic piston 144 is provided within the housing 143 upon the outer end of the shaft 142, an enlarged view of this structure being shown in Fig. 9 of the drawings. In the latter view, the piston 144 is shown as being hollow and substantially cylindrical, and as being connected to the shaft 142 by a suitable thrust bearing 145. A cap 146 forms the outer end of the housing 143 and encloses the outer end of the piston 144. As shown, both the housing and the cap are flanged at their point of joining and a domed diaphragm member 147 has its outer marginal edge or periphery 148 clamped and secured between the abutting faces of the cap and the housing. The central portion of the diaphragm is secured upon the face of the piston 144 by a plate 149 and bolts 150. As shown, the clearance between the piston and the housing and cap is sufficient to permit doubling of the diaphragm structure, whereby an effective sealing is obtained without the employment of piston rings or similar structures which are subject to leakage. The diaphragm structure may roll upon itself as the piston moves from the position shown in Fig. 9 to the position shown in Fig. 7, and a complete seal is maintained at all times. The hydraulic fluid conductor 38 (shown in Fig. 4) is connected into the outer end of the cap 146 and leads to the cylinder 36 and the piston 35 for operating the brake band 17.

It is often desirable to disconnect this entire control mechanism from the cable drum 16, and a structure for this purpose is shown in Fig. 8 of the drawings. In this modification, the worm gear 138 and the worm wheel 137 are mounted within the housing 136 in the manner illustrated in Fig. 7, and an operating shaft 151 projects through the side walls of the housing. The worm wheel 137 is rotatably mounted upon the shaft 151 by means of bearings 152, the shaft, in turn, being journaled in the walls of the housing upon bearings 153. Suitable oil seals 154 are provided to prevent oil leakage through the side walls of the housing around the shaft. A spline clutch 155 is keyed upon the shaft 151 and is adapted to engage a splined collar 156 formed integrally with the ratchet wheel 139. In the position of the elements shown in Fig. 8, the clutch is disengaged and the shaft 151 may turn independently of the ratchet wheel 139 and of the worm wheel 137. Upon shifting to the left, however, the clutch 155 engages the splined collar 156 and locks the elements against rotation with respect to one another.

A hydraulic or air pressure operated means is provided for shifting the clutch to and from its operating position, and includes a double-acting piston 157 engaging within a pair of opposed cylinders 158 carried upon the top wall of the housing 136. A link 159 connects the piston to an arm 160 which revolves a shaft 161 extending down one face of the housing 136 and carrying a suitable gear wheel 162 at its lower end. The gear wheel 162 meshes with a gear rack 163 which is reciprocally mounted within the wall of the housing 136 and the inner end of which has engagement with the clutch 155. Transverse shifting of the piston 157 in accordance with the admission of fluid under pressure to one of the cylinders 158 causes swinging of the arm 160, rotation of the shaft 161, and reciprocal movement of the gear rack 162. In this manner, the clutch 155 is moved into and out of engagement with the splined collar 156 so as to place the control de-

vice in operative or inoperative connection with the cable drum 16.

In the use of the preferred embodiment of the invention herein described, the cable drum may be run at any desired speed, or it may be set by adjustment of the weights 69 and 70 to place any desired load on the drill bit and to maintain such loading at a constant value.

The advantages and benefits flowing from the invention herein disclosed are manifold and involve many important factors in safety and ease of operation. As pointed out hereinbefore, the operating and control mechanism is subjected only to light loads of a frictional nature, and hence the elements of the system may be made quite small and relatively inexpensive. This permits the various elements of the device to be fabricated with high safety factors without involving expensive and heavy parts, thereby considerably reducing the probability of mechanical failure within the device. Nevertheless, should some mechanical failure occur, so as to stop the motor 48 or interrupt the flow of motive fluid under pressure flowing thereto, the motor will simply stop, thereby applying the brake and terminating the feed-off or payout of cable from the reel 16. In some existing devices using direct electrical control, hydraulic control, or electrically actuated brakes, a power failure will permit the paying-out of cable and so increase the load upon the drill bit so quickly that the drill pipe is twisted off before the operator can seize control of the drilling mechanism. In the present invention, the customary cable reel brake is employed for control of the cable drum or reel, and since the brake is already present and is designed to handle in an adequate fashion the loads and forces involved, the present invention does not require the provision of additional braking or control devices of sufficient massiveness and strength as to be capable of handling the heavy loads involved.

A further very important feature of the invention lies in the fact that the operator can instantly take over control of the drilling machine. It is only necessary to operate the brake lever by hand to take over the control, and there is no necessity of manipulating clutches, switches, valves, and the like to disengage the automatic control before taking over manual control. Indeed, if hoisting is required, the hoisting rig clutch may be engaged at once without stopping or altering the operation of the control device since the brake will be instantly released as soon as the cable drum begins to rotate to take in cable. Under emergency conditions, a few seconds delay in operation or manipulation of the drilling machinery may cause heavy damage, and no delay is encountered through use of the present invention.

It is further to be noted that so long as the automatic control device is in operation, there will be established a maximum rate of cable payout. Thus, should the drill bit or the drill stem suddenly break through into a void in the formation, dropping of the bit and the drill string will be prevented since the brake will instantly take hold and prevent such dropping. This is very important, especially in deep drilling where many tons of drill pipe are involved. Such large mass need only be dropped a small distance to do enormous damage. This control of maximum rate of feed-out is also important in reaming operations. In such cases, the entire load of the drill stem must be suspended from the drilling ma-

chinery, and the present device provides adequate control and regulation of such an operation.

The bypass valves 46 and 107 are of great value when controlled rapid shifting from upward to downward movement of the drill stem and from downward to upward movement thereof, are required, such as in fishing operations. The hoisting mechanism cannot get out of control when the present device is being employed, and very rapid shifting is facilitated by the ease of engagement and disengagement of the control mechanism with the drilling machine.

As pointed out hereinbefore, the adjustable mounting of the hydraulic cylinder 128 provides for compensation of the control device in accordance with the size cable being employed. This adjustability of the cylinder also is of importance in permitting exact calibration of the structure to permit direct reading from the scale 13 of the actual load upon the travelling block 13. In practice, the scale 13 is removable, and a plurality of such scales are provided in accordance with the number of lengths of cable from which the travelling block is suspended. After the proper scale has been attached, the empty travelling block hook may be balanced to zero upon the scale and then a known weight lifted by said hook. If the scale fails to balance at the setting of that known weight on the beam, the cylinder on the deadline anchor is shifted and adjusted by trial until the reading on the scale when balanced corresponds with the known weight. Accurate calibration of the device and adjustment thereof to a proper reading is thereby permitted and facilitated.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. Control apparatus for cable drums including, driving means, an element driven by said driving means, a second element adapted to be driven by the cable drum, a connection between the first and second elements, a support for the first element, the latter element being movable longitudinally of the support with respect to the second element, brake means for the cable drum, and a force-transmitting connection between the brake means and the first element whereby force for tightening the brake means is supplied by the cable drum through the connection between the first and second elements and through the force-transmitting connection to the brake means.

2. Control apparatus for cable drums including, driving means, a longitudinally shiftable worm gear driven by the driving means, a second gear adapted to be driven by the cable drum meshing with the worm gear, brake means for the cable drum, and a force-transmitting connection between the brake means and the worm gear whereby force for tightening the brake means is supplied by the cable drum through the worm gear and the second gear and through the force-transmitting connection to the brake means.

3. Control apparatus for cable drums including, driving means, an element driven by said driving means, a second element adapted to be driven by the cable drum, an operating connection between the elements, the first element being shiftable with respect to the second element,

brake means for the cable drum, and a movement-transmitting connection between the brake means and the first element for transmitting movement of the first element to the brake means, whereby movement and force to tighten the brake means is supplied from the cable drum through the connection between the first and second elements and through the movement-transmitting connection to the brake means.

4. A control apparatus for cable drums including, driving means, an element revolved by said driving means, a second element adapted to be revolved by the cable drum, a driving connection between the elements, a support for the first element permitting shifting of the latter with respect to the second element, brake means for the cable drum, and a movement-transmitting connection between the brake means and the first element for transmitting movement of the first element to the brake means, whereby movement and force to tighten the brake means is supplied from the cable drum through the connection between the first and second elements and through the movement-transmitting connection to the brake means.

5. Control apparatus as set forth in claim 4, and means for regulating the driving means.

6. Control apparatus as set forth in claim 4, and a splined connection between the driving means and the first element.

7. Control apparatus for drilling equipment having a hoisting cable carried by a cable drum and an anchor for the dead end of the cable, including, a driving motor adapted to be driven by fluid under pressure, a pressure fluid conductor leading to the motor, a metering valve in said conductor, operating means for the valve connected to the anchor, a coupling between the motor and the cable drum, brake means for the cable drum, and actuating means for the brake means connected to said coupling.

8. Control apparatus for drilling equipment having a hoisting cable carried by a cable drum and an anchor for the dead end of the cable, including, a driving motor adapted to be driven by fluid under pressure, a pressure fluid conductor leading to the motor, a metering valve in said conductor, operating means for the valve connected to the anchor, a coupling between the motor and the cable drum, brake means for the cable drum, and hydraulic actuating means for the brake means connected to said coupling.

9. Control apparatus as set forth in claim 7, wherein the coupling between the motor and the cable drum includes, an element revolved by the motor, a second element revolved by the cable drum, a driving connection between the elements, and a support for the first element permitting shifting of the latter with respect to the second element, the actuating means for the brake means being operated by the shifting of said first element.

10. Control apparatus as set forth in claim 7, wherein the coupling between the motor and the cable drum includes, a longitudinally-shiftable operating shaft driven by the motor and operating the brake actuating means, a worm gear on the shaft, and a worm wheel meshing with the worm gear adapted to be driven by the cable drum.

11. Control apparatus as set forth in claim 10, wherein the coupling between the motor and the cable drum includes, a first shaft driven by the motor, a second longitudinally-shiftable shaft splined to the first shaft and operating the brake

actuating means, a worm gear on the second shaft, and a worm wheel meshing with the worm gear adapted to be driven by the cable drum.

12. Control apparatus as set forth in claim 7, wherein the coupling between the motor and the cable drum includes, a speed changer driven by the motor, a first shaft driven by the speed changer, a worm gear, splines connecting the worm gear with the first shaft, a worm wheel meshing with the worm gear, a ratchet for connecting the worm wheel with the cable drum, and means connected with the worm gear for operating the brake actuating means.

13. Control apparatus as set forth in claim 7, wherein the anchor for the dead end of the cable includes, a support, a reel structure pivotally mounted on the support, means on the reel for securing the dead end of the cable thereto, a hydraulic cylinder carried by the support, and a piston in the cylinder having a piston rod, said rod being adapted to be actuated by the reel, and said cylinder being adjustable on the support toward and away from the pivotal center of the reel, the piston and cylinder comprising the operating means for the metering valve.

14. Control apparatus as set forth in claim 7, wherein the anchor for the dead end of the cable includes, a support, a reel structure receiving the cable tangentially, means on the reel for securing the cable thereto, said reel being eccentrically mounted for revolution upon the support about a center closely adjacent the point of tangency of the cable to said reel, the reel and support forming the two main elements of the anchor, a hydraulic cylinder carried by one of said main elements, and a piston in the cylinder having a piston rod engaging the other of said main elements, the point of engagement of the piston rod being relatively remote from the center of revolution of the reel, the piston and cylinder comprising the operating means for the metering valve.

15. Control apparatus as set forth in claim 7, wherein the anchor for the dead end of the cable includes, a support, a reel structure pivotally mounted on the support, means on the reel for securing the dead end of the cable thereto, the reel and the support forming the two main elements of the anchor, a hydraulic cylinder carried by one of said main elements, and pressure-exerting means in the cylinder having an operating stem engaging the other of said main elements, said operating stem being adjustable toward and away from the pivotal center of the reel, the pressure exerting means and the cylinder comprising the operating means for the metering valve.

16. Control apparatus as set forth in claim 7, wherein the anchor for the dead end of the cable includes, a fixed support, a movable support pivotally mounted upon the fixed support, a reel pivotally mounted upon the movable support, said reel receiving the cable tangentially, means for securing the reel against rotation with respect to the movable support, means on the movable support for securing the dead end of the cable, and pressure-indicating means associated with the movable and the fixed supports.

17. Control apparatus as set forth in claim 16, wherein the reel securing means includes a pin engageable with the movable support, the reel having a plurality of transverse openings adapted to receive said pin in a plurality of positions of the reel with respect to the movable support.

18. A control apparatus for cable drums in-

cluding, driving means, an element revolved by said driving means, a second element adapted to be revolved by the cable drum, a driving connection between the elements, a support for the first element permitting shifting of the latter with respect to the second element, brake means for the cable drum, actuating means for the brake means connected to the first element and operated by shifting thereof, and a ratchet connection between the cable drum and the second element.

19. A control apparatus for cable drums including, driving means, an element revolved by said driving means, a second element adapted to be revolved by the cable drum, a driving connection between the elements, a support for the first element permitting shifting of the latter with respect to the second element, brake means for the cable drum, actuating means for the brake means connected to the first element and operated by shifting thereof, and control means for regulating the driving means including, a source of fluid under pressure for operating the driving means, a pressure fluid conductor between said source and the driving means, and adjustable valve means in said conductor.

20. A control apparatus for cable drums including, driving means, an element revolved by said driving means, a second element adapted to be revolved by the cable drum, a driving connection between the elements, a support for the first element permitting shifting of the latter with respect to the second element, brake means for the cable drum, actuating means for the brake means connected to the first element and operated by shifting thereof, and control means for regulating the driving means including, a source of fluid under pressure for operating the driving means, a pressure fluid conductor between said source and the driving means, and a metering valve in said conductor.

21. Control apparatus for cable drums including, driving means operable at a selected speed, brake means for the cable drum arranged to be applied and released to maintain the speed of revolution of the drum at a predetermined ratio with respect to the speed of operation of the driving means, a motion-transmitting connection be-

tween the driving means and the cable drum, said connection including an element having a normal position occupied when the cable drum and the driving means are operating at the predetermined ratio, said element being mounted for shifting from its normal position when the relative speeds of operation of the cable drum and the driving means vary from said predetermined ratio, an actuating connection between said element and the brake for applying and releasing the brake means in accordance with the shifting of the element, and means for controlling the speed of operation of the driving means.

22. Control apparatus for cable drums including, brake means for the cable drum, driving means operable at a selected speed, a motion-transmitting connection between the driving means and the cable drum and having an element arranged to shift position when the speed of operation of the cable drum varies from a predetermined ratio with respect to the speed of operation of the driving means, the brake means being applied and released by the position shifting of said element, and means for controlling the speed of operation of the driving means.

23. A control apparatus as set forth in claim 22, a weight-responsive means responsive to the load sustained by the cable drum, and an operating connection between said weight-responsive means and the speed-controlling means for the driving means for maintaining a predetermined load on the cable drum.

JOHN C. SLONNEGER.
